(57) **CLAIM**

The ornamental design for a grease caddy, as shown and described.

DESCRIPTION

FIG. 1 is a front elevational view of a grease caddy showing my new design;

FIG. 2 is a top plan view thereof;

FIG. 3 is a right side elevational view thereof;

FIG. 4 is a rear elevational view thereof; and,

FIG. 5 is a bottom plan view thereof.

The left side elevational view, which is not illustrated, is a mirror image of the right side elevational view.
